UNITED STATES PATENT OFFICE.

CHARLES HOWARD HOOK, OF PITTSBURGH, PENNSYLVANIA.

GAS-BOILER.

1,089,131.

Specification of Letters Patent.

Patented Mar. 3, 1914.

Application filed September 30, 1913. Serial No. 792,642.

To all whom it may concern:

Be it known that I, CHARLES HOWARD Hook, a citizen of the United States of America, residing at Pittsburgh, in the county of Allegheny and State of Pennsylvania, have invented certain new and useful Improvements in Gas-Boilers, of which the following is a specification, reference being had therein to the accompanying drawing.

This invention relates to a gas boiler for heating water or generating steam and has for its object to provide a boiler of such class, with means, in a manner as herein-after set forth, whereby the flame from the burner will be deflected in a manner to thoroughly and quickly heat the water circulating through the tubes.

A further object of the invention is to provide a compact boiler unit presenting a large area or surface adapted to be impacted by the flame or products of combustion to obtain the quick heating of the water with a minimum expenditure of fuel.

A further object of the invention is to provide a compact boiler unit, in a manner as hereinafter set forth, wherein the water circulating therethrough will be thoroughly heated.

A further object of the invention is to provide a boiler unit including longitudinal superimposed water conduits all of which are shaped to baffle and deflect the heat or products of combustion and to so construct the conduits with respect to each other to provide a baffled path for the passage of the heat or products of combustion.

Further objects of the invention are to provide a gas boiler which is simple in its construction, and arrangement, strong, durable, efficient and convenient in its use, readily set up, and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings, wherein like reference characters denote corresponding parts throughout the several views:—Figure 1 is a perspective view of a gas boiler in accord-

ance with this invention, Fig. 2 is a perspective view of one of the boiler units, Fig. 3 is a section on line X—X, Fig. 2, looking in the direction of the arrow, and Fig. 4 is a section on line Y—Y, Fig. 2, looking in the direction of the arrow.

A gas boiler in accordance with this invention includes a plurality of units and as each unit is similar in construction, but one will be described.

Each unit consists of the form illustrated in Fig. 2 and includes a pair of hollow vertically disposed end walls 5—6, the latter being formed at its lower end with a tubular offset 7 which communicates with the wall 5 at the lower end, and the former is provided at its upper end with a tubular offset 8 which communicates with the top of the wall 6 by an opening 9. The end walls 5—6 are connected together at their upper ends by a hollow top wall 10 which provides a steam dome and which has its intermediate portion 11 of less width than its end portions. The end walls 5—6 are mounted at their lower ends upon a gas burner 12, the latter being provided with outlet ports 13 and a regulating valve 14. When a plurality of units are arranged in proximity in a manner as shown, the tubular offset 8 constitutes a steam or water outlet, while the tubular offset 7 constitutes a water inlet. The water inlet is adapted to be connected to a suitable source of supply, while the steam or water outlet is connected with the point of consumption. Each unit furthermore includes a series of superimposed water conduits which have their ends connected to the end walls 5 and 6 as well as communicating with the interior of the said end walls.

Certain of the water conduits are indicated by the reference character 15 and the other conduits by the reference character 16. Each of the conduits 15 is what may be termed substantially heart-shaped in cross section, and each of which has each end portion reduced as at 17 whereby the intermediate portion will be of greater area than the end portions. Each of the conduits 16 is rectangular in cross section and the intermediate portion thereof, as indicated at 17^a, is of less width than an end portion. The conduits 15—16 are alternately disposed with respect to each other and the end portions of the conduits 16 are arranged over the reduced end portions of the conduits 15, while the reduced portions 17^a of the

conduits 16 are positioned over the wide intermediate portions of the conduits 15. By this arrangement a circuitous passage is provided for the flame from the gas burner, or for the heat, or for the products of combustion and the flame is deflected so that it will heat the conduits throughout.

The reduced intermediate portions of the conduits 16 are connected to the enlarged intermediate portions of the conduits 15 by vertically disposed rectangular pipes 18, whereby communication is established between the central portions of the conduits 15 and the central portions of the conduits 16. The upper conduit 15 which is arranged in proximity to the steam dome, is connected to the latter by a pair of rectangular pipes 19, which establish communication between the intermediate portion of the upper conduit 15 and the enlarged end portions of the dome 10. The other conduits 15 have their intermediate portions connected to the end portions of the conduits 16 by a pair of vertically extending rectangular pipes 20 whereby communication is established between the end portions of the conduits 16 and the intermediate portions of the conduits 15 other than that conduit 15 which is connected to the steam dome. The pipes 18, 19 and 20 provide what may be termed by-passes between the conduits and between the upper conduit and the steam dome 10. The pipe 18 is twice the area of a pipe 19 or a pipe 20. The combined area of the reduced end portion of a conduit 15 equals the area of the reduced intermediate portion of a conduit 16. When a plurality of units are set up, the intermediate portions of the conduits 15 of one unit abut against the intermediate portions of the conduits 15 of the adjacent units and the end portions of the conduits 16 of one unit abut against the end portions of the conduits 16 of adjacent units as clearly illustrated in Fig. 1.

The reference character 21 denotes an inclosing casing for the gas burners 12 as well as a supporting casing for the units.

22 denotes side plates, and 23 a cover. The side plates are coupled together by the tie bars 24.

The reference character 25 denotes a gas supply pipe for the burners.

An outlet flue 26 is provided for the boiler.

It is apparent that a large number of units can be readily assembled for use in connection with a large boiler, or for a large hot-water radiating system, or for generating a large amount of steam, or that a single unit can be employed with side plates, whereby the unit can be used in a bath room for heating purposes and for heating the water to be used in the bath room.

What I claim is:—

1. A boiler including a unit comprising

a pair of hollow end walls, a steam dome connecting said walls at the top thereof, means communicating with one of said end walls to constitute an outlet, means communicating with the other end wall to constitute an inlet, and water conduits connecting said hollow end walls and communicating intermediate their ends with each other, one of said conduits provided with means for establishing communication therebetween and said steam dome. 70 75

2. A boiler including a unit comprising a pair of hollow end walls, a steam dome connecting said walls at the top thereof, means communicating with one of said end walls to constitute an outlet, means communicating with the other end wall to constitute an inlet, and water conduits connecting said hollow end walls and communicating intermediate their ends with each other, one of said conduits provided with means for establishing communication therebetween and said steam dome, certain of said conduits having their end portions reduced and the remaining of said conduits having their intermediate portions reduced. 80 85 90

3. A boiler including a unit comprising a pair of hollow end walls, a steam dome connecting said walls at the top thereof, means communicating with one of said end walls to constitute an outlet, means communicating with the other end wall to constitute an inlet, and water conduits connecting said hollow end walls and communicating intermediate their ends with each other, one of said conduits provided with means for establishing communication therebetween and said steam dome, certain of said conduits having their end portions reduced and the remaining of said conduits having their intermediate portions reduced, those conduits having their end portions reduced being heart-shaped in cross section, and the remaining conduits being rectangular in cross section. 95 100 105

4. A boiler unit comprising hollow end walls, one provided with means to constitute an outlet and the other provided with means to constitute an inlet, water conduits communicating at their ends with said walls, said conduits superimposed with respect to each other, and pairs of pipes and single pipes for establishing communication between said conduits, the pairs of pipes being alternately disposed with respect to the single pipes. 110 115 120

5. A boiler unit comprising a pair of hollow end walls, one provided with means to constitute an inlet and the other with means to constitute an outlet, a series of superimposed conduits communicating with and connected to said end walls, certain of said conduits having enlarged intermediate portions, said conduits having the enlarged intermediate portions being alternately dis- 125 130

posed with respect to the remaining conduits, a pair of pipes for establishing communication between the said intermediate portions and the other conduits, and a single pipe for establishing communication between the other conduits and said intermediate portions.

6. A boiler unit comprising a pair of hollow end walls, one provided with means to constitute an outlet and the other with means to constitute an inlet, a plurality of superimposed conduits communicating with said end walls, certain of said conduits having enlarged end portions and the other conduits having reduced end portions, the conduits provided with the enlarged end portions alternately disposed with respect to the conduits having the reduced end portions, single pipes for establishing communication between the enlarged and intermediate portions of the said conduits, and pairs of pipes for establishing communication between the enlarged intermediate portions of the conduits and the enlarged end portions of the conduits.

7. A boiler comprising a plurality of abutting units each including a pair of hollow end walls, one of said walls provided with means to constitute an inlet and the other of said walls provided with means to constitute an outlet, each of said units further including means connecting said end walls to constitute a steam dome, and a series of superimposed conduits communicating with said end walls, means intermediate the ends of the conduits of each unit for establishing communication therebetween, and means intermediate the ends of the upper conduit of each unit for establishing communication therebetween and the steam dome of its respective unit.

8. A boiler unit comprising a pair of hollow end walls, superimposed spaced conduits communicating at their ends with said

walls, alternately disposed pairs of vertically extending pipes for establishing communication between certain of the conduits, and alternately disposed vertically extending single pipes for establishing communication between the other of the conduits.

9. A boiler unit comprising a pair of hollow end walls, one provided with means to constitute an inlet and the other with means to constitute an outlet, superimposed conduits arranged between and communicating with said end walls, certain of said conduits having enlarged intermediate portions and the remaining conduits having reduced intermediate portions, the conduits with the enlarged intermediate portions alternately arranged with respect to the other conduits, and means intermediate the ends of said conduits for establishing communication therebetween.

10. A boiler unit comprising a pair of hollow end walls, one provided with means to constitute an inlet and the other with means to constitute an outlet, superimposed conduits arranged between and communicating with said end walls, certain of said conduits having enlarged intermediate portions and the remaining conduits having reduced intermediate portions, the conduits with the enlarged intermediate portions alternately arranged with respect to the other conduits, means intermediate the ends of said conduits for establishing communication therebetween, and a steam dome communicating with said end walls and further communicating with the upper of said conduits intermediate the ends of the latter.

In testimony whereof I affix my signature in the presence of two witnesses.

CHARLES HOWARD HOOK.
